CRANKSHAFT LAPPING MACHINE

Wallace H. Wood, Worcester, Mass., assignor to
Norton Company, Worcester, Mass., a corpora-
tion of Massachusetts

Application October 3, 1938, Serial No. 233,003

20 Claims. (Cl. 51—73)

The invention relates to abrading machines, and more particularly to a crankshaft lapping machine.

One object of the invention is to provide a simple and thoroughly practical lapping machine for simultaneously lapping or polishing a plurality of crankpins and main bearings on a crankshaft. A further object of the invention is to provide a crankshaft lapping machine in which 5 all of the crankpins and main bearings may be simultaneously lapped. Another object of the invention is to provide a crankshaft lapping machine for simultaneously lapping the crankpins and bearings of a crankshaft in which a plurality of lapping arms are hydraulically operated. 10

15 A further object of the invention is to provide a crankshaft lapping machine in which all of the bearing and crankpin lapping arms are mounted on a movable frame which is movable to and from an operating position by a hydraulically operated mechanism. A further object of the invention is to provide a hydraulically operated clamping mechanism for clamping the lapping arms in an indexed position during the loading 20 operation.

25 A further object of the invention is to provide a hydraulically operated footstock for aiding in supporting the work. A further object of the invention is to provide a single control valve for interlocking the various hydraulic mechanisms 30 of the machine. Another object of the invention is to provide a plurality of stops or latches to restrict the movement of the control valve so as to interlock the various hydraulically operated mechanisms of the machine so that all 35 must be operated in a definite and predetermined cycle.

The invention accordingly consists in the features of construction, combinations of elements, 40 and arrangements of parts, as will be exemplified in the structure to be hereinafter described, and the scope of the application of which will be indicated in the following claims.

In the accompanying drawings in which is 45 shown one of various possible embodiments of the mechanical features of this invention,

Fig. 1 is a front elevation of the improved crankshaft lapping machine;

Fig. 2 is an end elevation, on an enlarged scale, 50 of the improved crankshaft lapping machine;

Fig. 3 is a diagrammatic illustration of the hydraulic actuating mechanism and piping together with the control valve and the interlocking stop or latch mechanism therefor;

Fig. 4 is a horizontal sectional view through the hydraulic control valve, showing the valve in its second position during its rearward movement;

Fig. 5 is a vertical sectional view through the

control valve, showing the valve in its third position on its rearward movement;

Fig. 6 is a similar vertical sectional view, showing the control valve in its rearward or right-hand position;

Fig. 7 is a similar vertical sectional view, showing the control valve in its second position during its forward movement;

Fig. 8 is a similar horizontal sectional view, showing the control valve in its third position 10 during its forward movement;

Fig. 9 is a fragmentary sectional view showing the rear end of the control valve and latch mechanism in elevation;

Fig. 10 is a right-hand end elevation of the 15 headstock mechanism, on an enlarged scale;

Fig. 11 is a fragmentary sectional view taken approximately on the line 11—11 of Fig. 2, showing the lapping arm clamping mechanism;

Fig. 12 is a fragmentary end elevation of a 20 crank lapping arm and its supporting and clamping mechanism; and

Fig. 13 is a fragmentary cross sectional view, on an enlarged scale, taken approximately on the line 13—13 of Fig. 11.

25 A crankshaft lapping machine has been illustrated in the drawings comprising a base 20 which supports a longitudinally reciprocable work supporting table 21. Table ways are provided between the base 23 and the table 21 which in the preferred form are of an anti-friction type. 30 The base 20 is provided with a plate 26 which is fixed to the base 20 and is provided at its edge portions with grooves 27 and 28 which serve as inner raceways for a pair of spaced rows of anti-friction balls 29 and 30, respectively. A cage is provided between the races to space the balls 29 and 30 longitudinally, as desired. This construction forms an anti-friction way whereby the table 21 together with a headstock 22 and a footstock 23 40 may be readily reciprocated during the lapping operation.

Headstock

The headstock 22 is provided with a rotatable 45 spindle 33 which is supported in bearings (not shown). The headstock spindle 33 may be rotated from any suitable source of power, such as an overhead, belt drive, or a self-contained electric motor. In the preferred construction, an electric motor 34 is mounted in the base 20 of 50 the machine. The motor 34 is provided with a driving pulley 35 which is connected by multiple V-belts 36 with a pulley 37 on the headstock 22. The headstock construction has not been illustrated in detail in the present application since 55 this headstock is not considered to be a part of the present invention and, furthermore, is identical with that shown in the prior United States Patent No. 2,092,734 dated September 7, 1937, 60

to which reference may be had for details of disclosure not found herein.

Table reciprocation

5 In the lapping of crankpins and main bearings of an automotive crankshaft or the cams and main bearings of an automotive camshaft, it is desirable to provide a relative reciprocatory movement between the crankshaft or camshaft being lapped and the lapping or abrading element to prevent production of abrasive grain markings on the pins and bearings of the crankshaft. In the present case, the work table 21 is arranged for a longitudinal reciprocatory movement which is preferably accomplished by a translation of the rotary motion of the headstock spindle 33 into a reciprocatory movement of the table 21. The specific mechanism for reciprocating the table 21 has not been illustrated in the present case, since this mechanism is identical with that shown in the prior United States Patent No. 2,092,734 dated September 7, 1937, to which reference may be had for details of the table reciprocating mechanism not found herein.

25 *Footstock*

30 The other end of the crankshaft 24 is supported by the footstock 23 which is provided with a footstock center 51. The center 51 is carried by a rotatable spindle 52 which is journaled in bearings 53 and 54 within a hollow slidably mounted sleeve 55. The sleeve 55 is slidably keyed by means of a key 56 within an aperture in the footstock frame.

35 A fluid pressure actuated mechanism is provided for moving the footstock center 51 rapidly to and from an operative position to support one end of a crankshaft 24 within the machine. This mechanism comprises a fluid pressure cylinder 58 having a slidably mounted piston 59 contained therein. The piston 59 is connected to one end of a piston rod 60 which is connected to a pin 61. The central portion of the pin 61 is slabbed off on opposite sides so as to slide within an elongated slot 62 formed in the lower enlarged end of the piston rod 60. The pin 61 serves as a central pivotal connection between a pair of toggle levers 63 and 64. The toggle lever 64 is connected to the footstock frame by means of a stud 65. The other end of the toggle lever 63 is connected by a stud 66 with a slidably mounted hollow sleeve 67 which slides within an aperture 68 within the sleeve 55. The sleeve 67 is held against rotation by means of a pin 69 which is carried by the sleeve 55 and rides within an elongated slot in the sleeve 55. A spring 70 is contained within the sleeve 67 and is interposed between the end of an aperture of the sleeve 67 and a thrust collar 71.

60 When fluid under pressure is admitted through a pipe 72 to a cylinder chamber 73, the piston 59 is moved downwardly and the toggle levers 63 and 64 are moved from the dotted line positions 63a and 64a into the full line positions 63 and 64 (Fig. 3) which serves to move the sleeve 67 into the position illustrated. This movement serves to compress the spring 70 and, through the connecting parts, moves the sleeve 55 and footstock center 51 into operative supporting engagement with the end of the crankshaft 24. During this movement, fluid is exhausted from a cylinder chamber 74 through a pipe 75. The admission to and exhaust of fluid from the footstock operating cylinder 58 will be hereinafter described. This footstock is identical with that shown in the prior United States Patent No. 2,117,960 dated May 17, 1938, to

which reference may be had for details of disclosure not contained herein.

Lapping arm support

5 It is desirable to provide a movable support for a plurality of lapping arms so that they may be simultaneously and quickly moved into an operating or an inoperative position as desired. A pair of spaced arms 80, only one of which has been illustrated in the drawings (Fig. 2), are mounted 10 on a rock shaft 81 which is supported in bearings on the rear of the machine base 20. The arms 80 are provided with horizontally extending portions which are connected by two spaced bars 82 and 83 which serve as slide bars or ways for supporting a 15 plurality of lapping arms to be hereinafter described.

The lapping arm assembly supported by the arms 80 is arranged so that it may be automatically moved to and from an operating position to 20 facilitate loading of crankshafts into the machine and removing them therefrom after a lapping operation has been completed. In order to move the entire lapping arm assembly to an inoperative position, a fluid pressure mechanism is provided including a fluid pressure cylinder 84 which is pivotally connected by means of a stud 85 within the base 20 of the machine. A piston 86 is slidably mounted within the cylinder 84 and is connected to one end of a piston rod 87. The other end of the piston rod 87 is connected by a stud 88 with an arm 89 pivotally mounted on a shaft 90 supported within the base 20. The other end of the arm 89 is connected by a stud 91 to one end of a link 92. The other end of the link 92 is connected by a stud with a toggle lever 94. The adjacent ends of the toggle lever 94 and a toggle 95 are connected by a stud 93. The toggle lever 94 is connected at its other end by means of a stud 96 with the base 20. The toggle lever 95 is connected by a stud 97 with an arm 98 which is fixedly mounted on the rock shaft 81 and is arranged to rock the shaft 81 together with the arm 80 and all of the crankpin and bearing lapping arms together with their supporting and actuating mechanisms 45 either into or away from an operating position.

The levers 89, 92, 94 and 95, as shown in full lines in Fig. 2, are in a position to hold the arm 98 and the arms 80 together with the entire lapping arm assembly in an operating position. After a 50 lapping operation has been completed, fluid under pressure is admitted to the cylinder 84 to cause the piston 86 and piston rod 87 to move toward the right (Fig. 2) to shift the levers 89, 92, 94 and 95 and arm 98 into the dotted line positions 89a, 92a, 94a, 95a and 98a. This movement serves to rock the arms 80 in a clockwise direction (Fig. 2) to move the entire lapping arm assembly to an inoperative position.

60 *Fluid pressure system*

A fluid pressure system is provided to control the admission of fluid under pressure to the cylinder 84. A pump 99 within the base 20 of the machine draws fluid through a pipe 100 from a reservoir 101 within the base 20 and passes fluid under pressure through a pipe 102 to a reverse or control valve 103. The valve 103 is of a piston type having a valve stem 104 which is provided at its outer end with a spool-shaped member 105 and is connected by means of a pair of diametrically opposed studs or pins 106 mounted on a yoked end of a control lever 107. The control lever 107 is pivotally mounted on a stud 108 which is sup- 70 75

ported by a bracket 109 fixedly supported on the base 29 of the machine.

A plurality of valve pistons 110, 111, 112 and 113 are formed integral with the valve stem 104.

- 5 Fluid under pressure passing through the pipe 102 passes into a valve chamber 114 located between the valve pistons 111 and 112 and passes out through a pipe 115 into a cylinder chamber 116 within the cylinder 84 to cause the piston 86 to 10 move toward the left (Figs. 2 and 3) to shift the lapping arm support arms 80 in a counterclockwise direction (Fig. 2) to position the crankpin and bearing lapping arms in an operating position.

During the admission of fluid under pressure 15 to the cylinder chamber 116, fluid is exhausted from a cylinder chamber 117 at the other end of the cylinder 84, through a pipe 118, through a valve chamber 119 located between the valve pistons 112 and 113, and out through a pipe 120 20 into the reservoir 101. A fluid pressure relief valve 121 is connected by a pipe 122 with the pressure pipe 102 and serves to by-pass excess fluid under pressure within the pipe 102 to the reservoir 101.

25 The control valve 103 also serves to control the admission of fluid to the footstock actuating cylinder 58. The pipe 72 is connected to the pipe 115 and serves to convey fluid under pressure to the footstock cylinder chamber 73 simultaneously with the passage of fluid under pressure to the cylinder chamber 116 in the cylinder 84. The pipe 75 connects the cylinder chamber 74 of the cylinder 58 with the pipe 118 so that in the position of the control valve 103 (Fig. 3), 30 fluid will exhaust simultaneously from the cylinder chamber 74 in the cylinder 58 and from cylinder chamber 117 in the cylinder 84.

When the control valve 103 is shifted into the position illustrated in Fig. 3, fluid under pressure 35 enters both the cylinder 58 and the cylinder 84 and due to the fact that less power is required to move the footstock than the lapping arm assembly, the footstock center moves first into an operative position, after 40 which the lapping arm assembly moves to an operative position adjacent to the crankpins and bearings to be lapped.

Lapping arms

50 In order that all of the crankpins and main bearings on the crankshaft 24 may be simultaneously lapped, a plurality of crankpin and bearing lapping arms are provided which correspond in number with the crankpins and bearings to be lapped. As illustrated, there are three main bearing lapping arms 130, 131 and 132. There 55 are four crank lapping arms 133, 134, 135 and 136. The main bearing and crankpin lapping arms are supported in spaced relationship with each other so as to simultaneously engage and 60 lap the three main bearings and the four crankpins on the crankshaft 24.

The bearing lapping arms and crankpin lapping arms are substantially identical in construction. The bearing lapping arms are stationary while lapping the main bearing surfaces which are concentric with the axis of rotation of the crankshaft 24, whereas the crankpin lapping arms are rocked during the lapping operation due to the fact that they engage a crankpin which revolves about the axis of rotation of the crankshaft 24.

A side elevation of the lapping arm 132 is shown in Figs. 2 and 12. The lapping arm 132 75 as well as all of the other lapping arms are each

provided with a pair of pivotally mounted lap supporting arms 140 and 141 which are provided at their operative ends with partially cylindrical lap supporting blocks 142 and 143, respectively. The arms 140 and 141 are pivotally supported 5 by the studs 144 and 145 on the lapping arm 132. The other ends of the arms 140 and 141 are interconnected by means of a pair of toggle levers 146 and 147 which are connected together at their inner ends by means of a stud 148. The 10 stud 148 slides in an elongated slot 149 in the side plate of the lapping arm 132. When the toggle levers 146 and 147 are in a straight-line position (Fig. 2), the lap supporting members 142 and 143 are maintained in operative engagement 15 to hold an abrasive or lapping element in operative contact with a portion of the crankshaft 24.

The lapping supporting arms 140 and 141 are arranged to be automatically moved into and 20 away from an operative position, and in the preferred construction a hydraulically operated mechanism is provided for actuating the same comprising a fluid pressure cylinder 132a formed integral with the upper end of the lapping arm 25 132. A piston 132b is slidably mounted therein and is connected to one end of a piston rod 132c. The other end of the piston rod 132c is connected by a stud 150 with a link 151. The other end of the link 151 is connected to the stud 148 30 which pivotally connects the adjacent ends of the toggle levers 146 and 147. It will be readily apparent from the foregoing disclosure that when the piston 132b is moved downwardly, that is, toward the left (Fig. 2), the piston rod 132c 35 and the connecting link 151 will be moved also in a downward direction toward the left which serves to unlock the toggle levers 146 and 147 and thereby to rock the lap supporting arms 140 and 141 together with the lap supporting elements 142 and 143 to an inoperative position out of engagement with the crankshaft 24. When 40 fluid under pressure is passed through a flexible pipe 132d into a cylinder chamber 132e, the piston 132b will be moved upwardly to move the toggle levers 146 and 147 into a straight line position (Figs. 2 and 12) to move the abrasive lapping element into an operative position in engagement with the work piece 24 for a lapping operation. Similarly, when fluid under pressure 45 is admitted through a flexible pipe 132f to cause a downward movement of the piston 132b toward the left (Figs. 2, 3 and 12), the toggle levers 46 and 47 will be unlocked to move the lapping elements to an inoperative position. 50

It is to be noted in the drawings (Fig. 3) that each of the lapping arms is provided with an independent fluid operated piston and cylinder as well as piston rods which have been designated in the diagram with the same reference 55 numerals as the lapping arm on which it is mounted, the cylinders being designated by the letter *a*, the pistons by the letter *b*, the piston rods by the letter *c*, and cylinder chambers by the letter *e*.

It is desirable that all of the lapping elements represented by the supporting members 142 and 143 (Fig. 2) be moved into and away from an operating position simultaneously. This is preferably accomplished by providing a pair of longitudinally extending pipes or manifolds 153 and 154 which are fixedly supported on the spaced arms 80 and serve as a common source of fluid under pressure which may be forced either through the flexible pipe 132d to move the lap- 70 75

ping element into an operative position, or when the fluid under pressure is reversed, to flow through the flexible pipe 132*f* simultaneously to move all of the lapping elements to an inoperative position after the lapping operation has been completed. The admission to and exhaust of fluid from the manifolds or pipes 153 and 154 is controlled by the control valve 103. A pipe 155 is connected between the manifold or pipe 153 and the valve chamber 114 and serves in the position of the valve 103 (Fig. 3) to admit fluid under pressure to the manifold or pipe 153, into the cylinder chamber 132*e*, and simultaneously to all of the other corresponding cylinder chambers in the cylinders on each of the lapping arms to move and hold said lap supporting arms in an operative position for a lapping operation. A pipe 156 is connected between the manifold or pipe 154 and the valve chamber 119 so that in the position of the valve 103 (Fig. 3), fluid may be exhausted from the upper cylinder chambers on each of the lapping arms through the manifold 154 and the valve chamber 119, pipe 120, into the reservoir 101.

Each of the lapping arms 130 to 136 inclusive is pivotally supported. The details of the support for the lapping arms being identical, only one support has been illustrated in detail. An arm 165 is pivotally mounted on a supporting member 166 which is clamped in adjusted position on the guide rods 82 and 83. The lower end of the arm 165 is pivotally connected to the supporting member 166 by means of a pivotal connection 167. A pivotal connection 168 serves to connect the arm 165 with the lapping arm 132 so that the arm 132 is free to move. All of the lapping arms, both crankpin and main bearing arms, are mounted in the same manner so that when the lapping elements are clamped in lapping engagement with a crankpin and main bearing, the crank lapping arms may follow as the crankpin is revolved to produce the desired lapping action.

A flexible abrasive paper or cloth is preferably utilized as an abrading or lapping medium. Each of the lapping arms is provided with a separate strip of continuous abrasive paper which wraps around the crankpin or main bearing and is held in position thereagainst by the lap supporting members 142 and 143. A rod 170 is supported on the rear of each of the supporting members 166 by means of a bracket 171 and serves as a support for a reel 172 of flexible abrasive paper 173. The abrasive paper passes through guides 174 and 175 supported on the under side of the supporting member 166 and passes through a series of rollers 176 carried by a bracket 177. The abrasive paper above described wraps around a main bearing or crankpin of the crankshaft 24 and is supported by the lap supporting members 142 and 143. The worn or used abrasive paper is wound up on a reel 178 which is supported by a stud 179 carried by a bracket 180 supported on the lap supporting arm 140.

The lap supporting members 142 and 143 are mounted so that they may float or move relative to the arms 140 and 141, so that the lap supporting members 142 and 143 are self-aligning when brought into operative engagement to support the abrasive paper on a crankpin or main bearing for a lapping operation. The brackets 177 and 180 are fixedly mounted to the floating lap supporting members 142 and 143. A holding pawl 181 cooperating with a ratchet

wheel on the end of the reel 178 serves to prevent unreeling of the worn abrasive paper wound up on the reel 178 when the lap supporting arms are moved to and from an operating position. As illustrated in the drawings, the abrasive paper is fed manually when desired by the operator by manually turning the reel 178. Only one of the reels 178 and the associated parts to guide the abrasive paper through to the reel 178 have been illustrated in detail. Each lapping arm is provided with similar equipment supported on a separate supporting member 166. The abrasive paper and wind-up reels for each of the lapping arms are illustrated in the front elevation of the machine, as shown in Fig. 1.

The lapping arm 130 is supplied with a strip of abrasive paper 185 which is wound up on a reel 186. The lapping arm 133 is provided with a strip of abrasive paper 187 and the used portion thereof is wound up on a reel 188. The lapping arm 134 is supplied with a strip of abrasive paper 189, the used portion of which is wound up on a reel 190. The lapping arm 131 is supplied with a strip of abrasive paper 191, the used portion of which is wound up on a reel 192. The arm 135 is supplied with a strip of abrasive paper 193, the used portion of which is wound up on a reel 194. The lapping arm 136 is supplied with a strip of flexible abrasive paper 195, the used portion of which is wound up on a reel 196. Inasmuch as the abrasive paper supporting reels and the guiding means are identical for each of the lapping arms, only one of these mechanisms has been completely illustrated, as shown in Fig. 2.

It is desirable to provide a guiding means for guiding the lapping arms during their swinging movement as they follow the revolving crankpin and to provide a clamping mechanism to clamp all of the lapping arms in their indexed position relative to the supports 166 before the lap supporting members 142 and 143 are released from operative position and the lapping arm assembly swung to an inoperative position to facilitate loading of the machine. It is desirable to provide such a clamping device so that when the arms 80 are moved to an operating position after a new crankshaft has been loaded into the machine, all of the lapping arms will be in the proper indexed position so that the lap supporting members 142 and 143 may be automatically brought into engagement simultaneously with the crankpins and bearings of the crankshaft 24.

In order that the lapping elements may be guided in their swinging movement and held against lateral movement during the reciprocatation or oscillation of the crankshaft 24 during the lapping operation, a pair of parallel guiding plates 200 and 201 are fixedly mounted on the supporting bracket 166 and are spaced apart by a distance equal to the thickness of the lapping arm 132. The lapping arm 132 is guided thereby and is held against lateral movement by the guiding plates 200 and 201. The lapping arm 130 is similarly guided by the guiding plates 202 and 203. The lapping arm 133 is guided by guiding plates 204 and 205. The lapping arm 134 is guided by guiding plates 206 and 207. The lapping arm 131 is guided by guide plates 208 and 209. The lapping arm 135 is guided by guide plates 210 and 211, and the lapping arm 136 is guided by guide plates 212 and 213.

Lap arm-clamp device

clamping all of the crankpin and bearing lapping arms in their respective index positions, the guide plates 200, 202, 204, 206, 208, 210 and 212 are each provided with a groove or guideway 214 which supports a slidably mounted member 215 having cam surface depressions 216 formed therein. The guide plate 200 is provided with a pair of cams 217 and 218 which engage the cam shaped depressions 216 formed in the slidably mounted member 215. It will be readily apparent that if the slide 215 is moved upwardly (Fig. 11) relative to the guiding plate 200, the cam depressions 216 engaging the fixed cams 217 and 218 will cause the slide member 215 to move toward the right (Fig. 11) and thereby bind or clamp the lapping arm 132 in a fixed position relative to the guide plates 200 and 201. Each of the lapping arms 130 to 136 inclusive is provided with an identical clamping means, consequently only one of these clamps has been illustrated in detail. The guide plates 202, 204, 206, 208, 210 and 212 are each provided with a clamping slide 202a, 204a, 206a, 208a, 210a and 212a, respectively.

In order simultaneously to clamp all of the lapping arms, a mechanism is provided for simultaneously actuating the clamping slides 215, 202a, 204a, 206a, 208a, 210a and 212a. As illustrated in the drawings, a shaft 221 is rotatably supported in apertures in the guiding plates 200 to 212 inclusive. Each of the clamping slides is provided with an elongated slot 222 (Fig. 13). The shaft 221 carries an eccentric 223 which rides within the elongated slot 222. When the shaft 221 is rotated, the eccentric 223 rotating within the elongated slot 222 causes the clamping slide 215 to move relative to the guiding plates 200 and 201. The shaft 221 is provided with a plurality of eccentric members corresponding to the eccentric 223, each of which is arranged to engage elongated slots in the respective clamping slides 202a, 204a, 206a, 208a, 210a and 212a.

Clamp actuating motor

A vane type fluid pressure motor 230 is provided for rocking the shaft 221 to clamp and release the lapping arms. The motor 230 is provided with a rotor shaft 231 which supports a rotary vane 232. The rotor shaft 231 projects from the motor casing toward the left (Fig. 11). An arm 233 is supported on one end of the rotor shaft 231. The arm 233 is provided with an enlarged head 234 having a notch 235 formed in the outer end thereof. A lever 236 is fixedly mounted on the shaft 221 and is provided with a spring-pressed plunger 237 which is arranged to engage the notch 235 to lock the lever 236 to the lever 233 so that the rotation of the vane 232 of the motor 230 will be transmitted to rotate the shaft 221 to clamp or release the lapping arms. The plunger 237 is connected with a knob 238 by means of which the plunger 237 may be withdrawn from the notch 235 so that the clamping mechanism may be operated manually, if desired.

In order to attain one object of the invention, it is desirable to provide suitable interlocks so that the various mechanisms of the machine will operate in a predetermined sequence. When a crankshaft has been loaded into the machine, the control lever 167 is moved to shift the control valve 163 and start the cycle of operation. It is desirable that the various mechanisms should operate in the following sequence:

(a) Footstock center 51 moves in to grip the work.

(b) Arms 80 which support the crankpin and bearing lapping arms swing forward into an operating position.

(c) Jaws close onto work.

(d) Lapping arms unclamped.

(e) Headstock starts rotation, allowing work to rotate a predetermined number of rotations.

(f) Headstock stops rotation.

(g) Lapping arms are clamped in an indexed position.

(h) Jaws open.

(i) Arms 80 swing back to inoperative position.

(j) Footstock center 51 moves out of engagement with work to release the same, after which the crankshaft may be unloaded from the machine.

Interlocks

The ports in the valve 103 are so arranged that fluid under pressure will be admitted to the various hydraulic cylinders in the sequence above enumerated. It is, however, desirable that the various mechanisms have sufficient time to function before the next mechanism operates. It is, therefore, desirable to provide an interlocking of the various mechanisms which may comprise a series of stops which serve to limit the movement of the control valve when it is moved in either direction. These stops are interconnected with the various mechanisms so that after a mechanism has performed its function, the valve stop will be automatically withdrawn, thereby permitting a further movement of the control valve 103.

A stop collar 248 is fixedly mounted on the rear end of the valve stem 104. The collar 248 is arranged to slide within an aperture within a casing 249 mounted on the rear end of the casing of the valve 103. The casing 249 serves as a support for a plurality of spring-pressed stops which are arranged intermittently to stop the movement of the valve stem 104 when it is moved either towards the rear after a lapping operation has been completed or when the valve is moved forward after a new crankshaft has been loaded into the machine to start a lapping operation. As shown in Fig. 3, the valve 103 together with the other mechanisms of the machine are shown in the position during the lapping operation.

When the valve stem 104 is in the forward position (Fig. 3), a stop pawl 250 serves to prevent shifting the valve toward the rear to stop the lapping operation. The stop plunger 250 is connected by a link 251 to one arm of a bell crank lever 252 which in turn is connected by a flexible cable commonly known as a Bowden wire 253 with one arm of a bell crank lever 254. The bell crank lever 254 is mounted on the outer end of a clutch operating shaft 255 on the headstock 22 which is connected to move a clutch 256 into or out of engagement to start the headstock rotation. As shown in the drawings (Figs. 3 and 10), the headstock clutch is engaged and the crankshaft is being lapped. This lapping operation continues until a counting mechanism contained within the headstock 22 above referred to automatically stops the headstock after the crankshaft has been rotated a predetermined number of rotations for a lapping operation. When the clutch 256 is disengaged to stop the headstock rotation, the shaft 255 and bell crank 254 are rocked in a clockwise direction and this movement serves to pull on the flexible cable 253 to rock the bell crank 252 in a

counterclockwise direction and thereby automatically withdraw the stop plunger 250 from the path of the stop collar 248. During the lapping operation when the headstock is running, the 5 stop plunger 250 prevents accidental shifting of the valve towards the rear and holds it locked in a forward operating position.

The valve stem 104 may then be shifted until the stop collar 248 engages a stop plunger 269 10 which is arranged in a manner to be hereinafter described to prevent further rearward movement of the valve until the lapping arms are clamped in position. The spring-pressed stop plunger 290 is connected by a link 261 with one arm of a bell 15 crank lever 262, the other arm of which is connected to a flexible cable or Bowden wire 263. A spring 264 normally tends to move the bell crank in a clockwise direction. The Bowden wire or flexible cable 263 is wound partially around 20 the periphery of a disk 266 which is mounted on the end of the shaft 221 and is connected by means of a screw 265 with the periphery of the disk 266 (Fig. 11). The valve stem 104 cannot be moved further toward its rearward position 25 until fluid under pressure admitted through a pipe 305 actuates the clamping motor 230 and thereby clamps the lapping arms in an indexed position. The motor 230 rotates in a clockwise direction (Fig. 3) to clamp the lapping arms 30 and this movement also rotates the shaft 221 and the disk 266 also in a clockwise direction which 35 serves to pull the flexible cable or Bowden wire 263 toward the left (Fig. 3), thus rocking the bell crank lever 262 in a counterclockwise direction which serves automatically to withdraw the stop plunger 269 out of the path of the stop collar 248.

The valve stem 104 may then be moved rearwardly until it is again stopped by the stop collar 248 engaging the stop plunger 270. The 40 plunger 270 is connected by a link chain 271 with one arm of a bell crank lever 272, the other arm of which is connected to a flexible cable or Bowden wire 273. The other end of the Bowden wire or cable 273 is connected to the stud 148 45 which connects the toggle levers 146 and 147 with the hydraulic actuating mechanism. The valve stem 104 cannot be moved further to the rear until fluid under pressure admitted through the pipe 156 into the manifold or pipe 154 causes 50 a downward movement of all of the pistons 130b, 133b, 134b, 131b, 135b, 136b and 132b to actuate the toggle levers and open the lamp supporting arms or jaws. The downward movement of all of 55 these pistons serves through the Bowden wire 273 to rock the bell crank lever 272 in a clockwise direction (Fig. 3) which in turn, through the link chain 271, automatically withdraws the stop plunger 270 from the path of the stop collar 248.

60 After the plunger 270 has been withdrawn from the path of the stop collar 248, the valve stem 104 may then be shifted into its extreme rearward position, namely that shown in Fig. 6, so as to admit fluid under pressure through the pipe 118 into the cylinder chamber 117 of the cylinder 84 to rock the arms 88 so as to simultaneously withdraw the entire lapping arm assembly to an inoperative 65 position. At the same time the arms 88 withdraw the lapping arm assembly to an inoperative position, fluid under pressure is admitted through the pipe 75 to actuate the piston 59 and withdraw the footstock center 51. In this position of the parts, the crankshaft which has just been lapped may be removed from the machine.

70 After a new shaft has been inserted in the ma-

chine, the lever 167 is then moved in a clockwise direction (Fig. 2) to cause a forward movement of the valve, that is, toward the left (Fig. 7). The valve stem 104 can be moved until the stop collar 248 engages a stop plunger 280 which prevents further forward movement of the valve. This forward movement of the valve is sufficient to uncover the port and admit fluid under pressure through the pipe 115 into the cylinder chamber 116 of the cylinder 84 to cause the arms 88 10 supporting the lapping arm assembly to move to an operating position. The stop plunger 280 is connected by a link chain 281 with a bracket 282 which is fixed to the lever 95. When the lever 95 is moved into the position illustrated in Fig. 2, 15 the stop plunger 280 is moved downwardly (Fig. 3), thus permitting a further forward movement of the valve stem 104 until the stop collar 248 engages a stop plunger 300. The stop plunger 300 is connected by a link 301 with a bell crank lever 20 302 which is also connected to the Bowden wire or flexible cable 273.

The movement of the valve stop collar 248 into engagement with the stop plunger 300 serves to uncover a port so as to admit fluid under 25 pressure through the pipe 155 to manifold or pipe 153 and thereby admit fluid under pressure to the lapping arm cylinders to close the lap supporting arms or jaws into operating engagement with the work. This closing movement causes the pin 148 to move upwardly (Fig. 30 3) into the position illustrated therein which serves through the Bowden wire 273 to rock the bell crank lever 302 in a counterclockwise direction automatically to withdraw the stop 35 plunger 300 out of the path of the stop collar 248, thus permitting the valve stem 104 to be moved further in a forward direction, that is, toward the left (Fig. 3) until it uncovers a port to admit fluid under pressure through the pipe 40 304 to actuate the lapping arm clamping motor 230 to unclamp the lapping arms. This movement rotates the shaft 221 and the disk 266 in a counterclockwise direction which serves through a Bowden wire or flexible cable 310 to 45 rock a lever 311 which is pivotally mounted on a stud 312 on the headstock in a clockwise direction into the position illustrated in Fig. 3, thus shifting the lever 311 out of the path of a projection 313 on the bell crank lever 254, which 50 renders the headstock operative. In this position of the parts, the headstock control lever 320 may then be rocked to start the rotation of the headstock and the crankshaft 24 to be lapped. The lapping operation continues until the counting mechanism within the headstock, after a predetermined number of rotations of the crankshaft, again stops the rotation thereof, after which the cycle of operation of the valve and its interlocking plungers is again repeated.

After the headstock has been stopped by shifting of the clutch, the bell crank lever 254 rocks in a clockwise direction (Fig. 10) and when the hydraulic motor 230 is actuated to rotate the shaft 221 and the disk 266 to clamp all of the 65 lapping arms in an indexed position, the Bowden wire or flexible cable 310 is pulled to rock the lever 311 in a counterclockwise direction, that is, downwardly, as shown in Fig. 3, until a portion of the lever 311 lies in the path of the end 313 70 of the bell crank lever 254 so as to prevent starting the headstock rotation when the lapping arms are in a clamped position. It will thus be seen that by providing a plurality of stop plungers to cause a restricted movement of the valve stem 75

104 both on its rearward and forward movements, all of the various mechanisms of the machine are interlocked so that they must all be actuated in a definite and predetermined 5 sequence.

When the valve 103 is in the position illustrated in Fig. 3, fluid under pressure entering through the pipe 102 enters a valve chamber 114 between the valve pistons 111 and 112 and may 10 pass through the pipes 115, 155 and 304 to the various mechanisms of the machine. In this position of the valve, fluid may exhaust from the other side of the various fluid cylinders through the pipes 118, 156 and 305, into the valve chamber 119 located between the valve pistons 112 and 113 and pass out through the exhaust pipe 120 to the reservoir 101. Similarly, when the valve 15 is shifted into its other extreme position (Fig. 6), fluid under pressure passing through the pipe 102 enters the valve chamber 114 located between the pipes 118, 156 and 305. At the same time, fluid 20 may exhaust through the pipes 115, 155 and 304 through a valve chamber 320 and out through an exhaust pipe 321 which connects with the pipe 120 to return the exhaust fluid to the reservoir 101.

The operation of this improved machine will be readily apparent from the foregoing disclosure. A work piece, such as a crankshaft 24, to be 30 lapped is laid in position on a cradle 330 which is supported on the table 21 between the head 22 and footstock 23, and the flange on the crankshaft is positioned with the aligning hole in engagement with a drive pin on the headstock. In 35 this position of the valve, the valve stem 104 is in its rearward position. The control lever 107 is then moved in a clockwise direction to move the valve stem toward the left (Figs. 2 and 3), which movement operates first to admit fluid under 40 pressure through the pipe 115 and pipe 72 to move the footstock center 51 into supporting engagement with the end of the work piece. At the same time, fluid passing through the pipe 115 enters the cylinder chamber 116 to cause a down- 45 ward movement of the piston 86 (Fig. 2) to move the toggle levers 94 and 95 from their dotted line position into the full line position (Fig. 2) to rock the arms 88 and the entire lapping arm assembly into an operating position, which movement withdraws the stop plunger 280 and permits 50 further movement of the valve. The lever 107 is moved to a further extent and fluid under pressure is admitted through the pipe 155 to the manifold or pipe 153 which conveys fluid to all 55 of the lapping arm cylinders to actuate the toggle levers on each arm and thereby to swing the lap supporting arms or jaws into an operating position to hold the lapping element, namely the strips of abrasive paper, in lapping engagement 60 with all of the crankpins and bearings of the shaft. This movement serves through the Bowden wire or cable 273 to rock the bell crank lever 302 in a counterclockwise direction to withdraw the stop plunger 300, thus permitting a further 65 movement of the valve stem 104 toward the left (Fig. 3). The continued movement of the valve serves to open a port and admit fluid under pressure through the pipe 304 to the lapping arm clamp motor 230 which rotates the shaft 221 and 70 the disk 266 to unclamp the lapping arms. Rotation of the disk 266 in a counterclockwise direction serves through the Bowden wire or flexible cable 310 to rock the lever 311 in a counter-clockwise direction so that it is out of the path of 75 the projection 313 of the bell crank lever 254

which renders the headstock mechanism operative and by manual shifting of the lever 320, the headstock may be set in rotation to start the lapping operation on all of the crankpins and main bearings. The lapping operation continues 5 for a definite number of rotations of the shaft, after which a counting mechanism within the headstock 22 automatically disengages the headstock clutch 256.

During the lapping operation, the stop plunger 10 250 is in an operative position so as to prevent accidental shifting of the valve 104 toward the right (Fig. 3). When the headstock is automatically stopped by the counting mechanism, the bell crank lever 254 (Fig. 3) is rocked in a clockwise direction which serves to rock the bell crank lever 252 in a counterclockwise direction and thus withdraw the stop plunger 250 so that the valve stem 104 may be moved toward the rear or toward the right (Fig. 3). The lever 107 may 20 then be moved in a counterclockwise direction to move the valve stem 104 toward the right (Fig. 3), which movement continues until the stop collar 248 engages the stop plunger 260. During this movement, the valve shifts so as to 25 admit fluid under pressure through the pipe 305 to the lapping arm clamp motor 230 to rotate the shaft 221 in a clockwise direction to clamp all of the lapping arms in an indexed position. This movement serves to pull the Bowden wire 30 or flexible cable 310 to cause a counterclockwise movement of the lever 311 to swing downwardly into the path of the projection 313 of the bell crank 254 and thus lock the headstock so as to prevent starting work rotation while all of the 35 lapping arms are clamped in an index position.

At the same time, the rotation of the disk 266 in a clockwise direction pulls the Bowden wire or cable 263 to move the bell crank 262 in a counterclockwise direction and thereby withdraw the stop plunger 260, thus permitting a further rearward movement of the valve stem 104. The valve stem 104 may then be moved until the stop collar 248 engages the stop plunger 270 which serves to open a port so as to admit fluid under pressure 40 through the pipe 156 into the manifold or pipe 154 which causes a downward movement of all of the pistons within the lapping arm cylinders to actuate all of the toggle levers and to open the lap supporting members or jaws. During the 45 opening of the lap supporting members or jaws, the cable 273 is pulled to rock the bell crank lever 272 in a clockwise direction (Fig. 3) to withdraw the stop plunger 270, thus permitting the valve stem 104 to be moved into its extreme rearward 50 position. This movement of the valve stem serves to open a port so as to admit fluid under pressure through the pipe 118 into cylinder chamber 117 of the cylinder 84 to cause the arms 88 to swing the entire lapping arm assembly to an inoperative 55 position, after which the crankshaft which has been lapped may be removed from the machine.

It will thus be seen that there has been provided by this invention apparatus in which the various objects hereinabove set forth together 60 with many thoroughly practical advantages are successfully achieved. As many possible embodiments may be made of the above invention and as many changes might be made in the embodiment above set forth, it is to be understood that all 65 matter hereinbefore set forth or shown in the accompanying drawings is to be interpreted as illustrative and not in a limiting sense.

I claim:

1. In a lapping machine having a plurality of 75

lapping arms, a movable frame to support said arms, a clamping mechanism for clamping said arms relative to said frame, a rotatable work support including a motor driven headstock and a footstock, means including a manually operable clutch to start said headstock, a plurality of fluid motors respectively connected to actuate said footstock, said frame, said lapping arms and said clamping mechanism, a single manually operable control valve to control the admission to and exhaust of fluid from all of said motors, and a stop device to hold said control valve in an operating position during rotation of the headstock.

2. In a lapping machine having a plurality of lapping arms, a movable frame to support said arms, a clamping mechanism for clamping said arms in an indexed position relative to said frame, a rotatable work support including a motor driven headstock and a footstock rotatably to support a crankshaft therebetween, a clutch mechanism to start said headstock, a plurality of fluid pressure actuated motors respectively connected to actuate said footstock, said frame, said lapping arms and said clamping mechanism, a manually operable control valve operatively connected to control the admission to and exhaust of fluid from all of said motors, a stop to hold said control valve in an operative position during rotation of the headstock, and an automatically actuated mechanism to withdraw said stop when said headstock clutch is disengaged after completion of a lapping operation.

3. In a lapping machine having a plurality of lapping arms, a movable frame to support all of said arms, a clamping mechanism for clamping said lapping arms in an indexed position relative to said frame, a rotatable work support including a motor driven headstock and a footstock rotatably to support a crankshaft to be lapped, a plurality of fluid pressure actuated motors respectively connected to said footstock, said frame, said lapping arms and said clamping mechanism, a manually operable control valve operatively connected to control the admission to and exhaust of fluid under pressure from all of said motors, a spring pressed stop to hold said control valve in an operative position during rotation of said headstock, and connections between said clutch and said stop whereby said stop is automatically withdrawn when the clutch is moved to stop rotation of the headstock.

4. In a lapping machine having a plurality of lapping arms, a movable frame to support said lapping arms, a clamping mechanism to clamp said lapping arms relative to said frame, a rotatable work support including a motor driven headstock and a footstock, means including a manually operable clutch to start said headstock, a plurality of fluid motors respectively connected to said footstock, said frame and said lapping arms, a manually operable control valve to control the admission to and exhaust of fluid from all of said motors, and an interlock between said headstock clutch and said lapping arm clamping mechanism which serves to prevent starting said headstock when the lapping arms are clamped.

5. In a lapping machine having a plurality of lapping arms, a movable frame to support said lapping arms, a clamping mechanism to clamp said lapping arms relative to said frame, a rotatable work support including a motor driven headstock and a footstock, means including a manually operable clutch to start said headstock, a plurality of fluid motors respectively connected to said footstock, said frame and said lapping arms,

arms, a manually operable control valve to control the admission to and exhaust of fluid from all of said motors, an interlock between said headstock clutch and said lapping arm clamping mechanism which serves to prevent starting said headstock when the lapping arms are clamped, and a stop to limit the movement of said control valve to prevent movement of said valve during the rotation of said headstock. 5

6. In a lapping machine having a plurality of lapping arms, a movable frame or carrier to support said arms, a clamping mechanism for clamping said arms in an indexed position relative to said frame, a rotatable work support including a motor driven headstock and a footstock, means including a manually operable clutch to start said headstock, a plurality of fluid motors respectively connected to actuate said footstock, said frame, said clamping mechanism and said lapping arms, a manually operable control valve to control the admission to and exhaust of fluid from all of said motors, a stop to limit the movement of said valve in one direction, and automatically actuated mechanism actuated by releasing the lapping arms from the work to withdraw said stop so as to facilitate movement of said valve to its rearward position to admit fluid under pressure to the frame motor and move the frame and lapping arm supported thereby to an inoperative position. 30

7. In a lapping machine having a plurality of lapping arms, a movable frame or carrier to support said arms, a clamping mechanism for clamping said lapping arms in an indexed position relative to said frame, a rotatable work support including a motor driven headstock and a footstock, means including a manually operable clutch to start said headstock, a plurality of fluid motors respectively connected to actuate said footstock, said frame, said clamping mechanism and said lapping arms, a manually operable control valve to control the admission to and exhaust of fluid from all of said motors, a stop to limit the rearward movement of said valve during the lapping operation, means actuated by the stopping of said headstock automatically to withdraw said stop, a second stop to limit said control valve which serves to prevent movement of the valve to withdraw said frame until the lapping arms have been released from the work, and automatically actuated mechanism actuated by releasing the lapping arms from the work to withdraw said stop so as to facilitate movement of said valve to its rearward position to admit fluid under pressure to the frame motor to move the frame and the lapping arms supported thereby to an inoperative position. 45 50 55

8. In a lapping machine having a plurality of lapping arms, a movable frame to support said arms, a rotatable work support including a clutch controlled headstock and a footstock, a plurality of fluid motors respectively connected to said footstock, said lapping arms, and said frame, a manually operable control valve to control the admission to and exhaust of fluid from said motors, and a stop to limit the movement of the control valve in one direction so as to prevent admission of fluid to actuate the lapping arms until the frame is in an operative position. 60 65

9. In a lapping machine having a plurality of lapping arms, a movable frame or carrier to support said arms, a rotatable work support including a motor driven headstock and a footstock, a plurality of fluid motors respectively connected to said headstock, said frame and said lapping arms, 70 75

a manually operable control valve to control the admission to and exhaust of fluid from all of said motors, a stop to limit the movement of the control valve in one direction to prevent the admission of fluid to actuate said lapping arms until the frame is in an operative position, and means automatically actuated by movement of said frame into an operating position to withdraw said stop and thereby facilitate further movement of the control valve.

10. In a lapping machine having a plurality of lapping arms, a movable frame to support said arms, a rotatable work support including a motor driven headstock and a footstock, means including a manually operable clutch to start said headstock, a plurality of fluid motors respectively connected to said footstock, said frame and said lapping arms, a manually operable control valve to control the admission to and exhaust of fluid from all of said motors, a movable stop to prevent engagement of the headstock clutch to rotate the work until the lapping arms are in operative engagement with said work, and automatically actuated means actuated by movement of said lapping arms into operative engagement with the work to withdraw said stop so as to facilitate starting of the lapping operation by engagement of the headstock clutch.

11. In a lapping machine having a plurality of lapping arms, a movable frame or carrier to support said arms, a clamping mechanism to clamp said arms in an indexed position relative to said frame, a rotatable work support including a motor driven headstock and a footstock, means including a manually operable clutch to start said headstock, a plurality of fluid motors respectively connected to said footstock, said frame, said clamping mechanism and said lapping arms, a manually operable control valve to control the admission to and exhaust of fluid from all of said motors, a stop to limit the movement of said control valve in one direction until the admission of fluid to said frame motor moves the frame and lapping arms carried thereby into an operative position, means actuated automatically by said frame when it is moved into an operating position to withdraw said stop, a second stop to limit the forward movement of said frame during admission of fluid to said lap arm motors to close said laps on a shaft to be lapped, means actuated automatically by closing of said laps automatically to withdraw said second stop to facilitate a further movement of said control valve to admit fluid under pressure to said lap motor to unclamp said arms, an interlock between said clamp mechanism and said headstock clutch including a stop to prevent engagement of said clutch until actuation of the clamping mechanism to unclamp the lapping arms, and means actuated automatically by said clamping mechanism to withdraw said third stop, thereby rendering said headstock operative to facilitate manual actuation of the headstock clutch to start the lapping operation.

12. In a lapping machine as claimed in claim 1, the combination with the parts and features therein specified, of a stop to limit the movement of the control valve in one direction during rotation of the headstock and means automatically actuated by disengagement of the headstock clutch to withdraw said stop to facilitate movement of the control valve.

13. In a lapping machine as claimed in claim 1, the combination with the parts and features therein specified, of a stop to limit the movement 75 of the control valve in one direction during rota-

tion of the headstock and connections between said headstock clutch and said stop whereby the stop is moved automatically to an inoperative position when the clutch is disengaged.

14. In a lapping machine as claimed in claim 1, 5 the combination with the parts and features therein specified, of a stop to limit the movement of the control valve in one direction during actuation of the clamping mechanism and means automatically actuated by said clamping mechanism to withdraw said stop to facilitate further movement of the control valve.

15. In a lapping machine of the type set forth in claim 1, the combination with the parts and features therein specified, of a stop to limit the 15 movement of the control valve in one direction during actuation of the lapping arm clamping mechanism and connections between said clamping mechanism and said stop automatically to withdraw said stop to an inoperative position 20 when the clamping mechanism is actuated to clamp the lapping arms so as to facilitate a further movement of the control valve.

16. In a lapping machine as claimed in claim 1, the combination with the parts and features 25 therein specified, of a stop to limit the movement of the control valve in one direction during opening of said lapping arms and means automatically actuated by the opening of said lapping arms to withdraw said stop to facilitate further movement of the control valve.

17. In a lapping machine as claimed in claim 1, the combination with the parts and features therein specified, of a stop to limit the movement of the control valve in one direction during 35 the opening of said lapping arms and connections between said lapping arm actuating mechanism and said stop automatically to withdraw said stop to an inoperative position when the lapping arms are opened after a lapping operation has been 40 completed to facilitate a further movement of the control valve.

18. In a lapping machine as claimed in claim 1, the combination with the parts and features therein specified, of a stop to limit the movement 45 of the control valve in one direction during movement of the frame and lapping arm assembly to an operative position, and means automatically actuated by movement of said frame to an operative position automatically to withdraw said stop 50 to facilitate a further movement of the control valve.

19. In a lapping machine as claimed in claim 1, the combination with the parts and features therein specified, of a stop to limit the movement 55 of the control valve in one direction during the movement of the frame and lapping arm assembly into an operative position, and connections including a link chain connected between said frame and said stop automatically to withdraw 60 said stop to an inoperative position when the frame and lapping arm assembly are moved into an operative position to facilitate a further movement of the control valve.

20. In a lapping machine as claimed in claim 1, 65 the combination with the parts and features therein specified, of a control valve, a stop to limit the movement of the control valve in one direction during closing of the lapping arm jaws to prevent unclamping the lapping arms and 70 starting of the headstock, and connections between the lapping arm jaws and said stop automatically to withdraw said stop to facilitate a further movement of the control valve.
